UNITED STATES PATENT OFFICE.

WILLIAM H. WARNER, OF MELVERN, KANSAS.

DESIGN FOR A WOVEN-WIRE FENCE-PANEL.

SPECIFICATION forming part of Design No. 26,290, dated November 17, 1896.

Application filed August 31, 1896. Serial No. 604,498. Term of patent 14 years.

To all whom it may concern:

Be it known that I, WILLIAM H. WARNER, a citizen of the United States, residing at Melvern, in the county of Osage and State of Kansas, have invented a new and original Design for Woven-Wire Fence-Panels, of which the following is a specification.

This invention relates to a new and original design for woven-wire fence-panels; and it has for its object to provide a design of this character that shall be both useful and ornamental.

The leading feature of the design resides in a woven-wire fence-panel having a series of longitudinal and transverse wires intersecting with each other to form vertically-alined rows of quadrilateral figures, the alternate quadrilateral figures in the longitudinal rows thereof being arranged in the same horizontal plane, and said figures in the upper and lower horizontal rows being bounded at one side by twisted strands, said longitudinal wires of the panel being provided at the corners of the quadrilateral figures with straight or reversely-inclined oblique portions, and the transverse wires of the panel being provided with open spiral coils encircling said oblique portions of the longitudinal wires, said transverse wires also bounding two sides of the quadrilateral figures by inclined portions disposed at direct right angles to the oblique portions of the longitudinal wires.

In the drawing the figure is a plan view of a woven-wire fence-panel embodying the herein-described design.

Referring to the drawing, the numerals 1 and 2 respectively designate intersecting longitudinal and transverse wires forming alined rows of quadrilateral figures 3, the alternate figures 3 in the longitudinal rows 4 thereof being arranged in the same horizontal plane, and said figures in the upper and lower longitudinal rows being bounded at one side by twisted strands 4, provided with pointed projections 5. The wires 1 are provided with oblique portions 6, which are alternately reversely inclined, whereby reversely-inclined oblique portions 6 will be disposed, respectively, at opposite corners of each figure 3. Open spiral coils 7 of the wires 2 encircle the portions 6, and the inclined portions 2 between the wires 1 are disposed at direct right angles to the oblique portions 6.

What I claim is—

The design for a woven-wire fence-panel herein shown and described.

In testimony that I claim the foregoing as my own I have hereto affixed my signature in the presence of two witnesses.

WILLIAM H. WARNER.
